UNITED STATES PATENT OFFICE.

JAMES M. C. TYNER, OF ELLENDALE, DAKOTA TERRITORY.

SPARK-ARRESTER.

SPECIFICATION forming part of Letters Patent No. 369,483, dated September 6, 1887.

Application filed February 15, 1887. Serial No. 227,705. (No model.)

To all whom it may concern:

Be it known that I, JAMES M. C. TYNER, a citizen of the United States of America, residing at Ellendale, in the county of Dickey 5 and Territory of Dakota, have invented certain new and useful Improvements in Spark Arresters for Steam-Engines, of which the following is a specification, reference being had therein to the accompanying drawings.

10 My invention relates to improvements in spark-arresters for steam-engines; and it consists in certain novel features of construction, which will first be described in connection with the accompanying drawings and then 15 pointed out in the claims.

Figure 1 of the drawings is a vertical sectional view of the smoke-stack and its head with the arrester in place. Fig. 2 is a perspective view of the arrester. Fig. 3 is a 20 detail view.

Referring to the drawings, A represents the smoke stack, and B its head, of any ordinary form, but preferably of the form shown, which is riveted to the stack considerably below the 25 upper end of the latter—that is to say, the stack extends some distance up into the head—for a purpose which will hereinafter appear. A short outlet-pipe, C, communicates with the interior of the head at a point as near as 30 possible to the junction of the latter with the smoke-stack, and is provided on either side with a short pin, c.

D represents a conduit-pipe slotted at its upper end, as shown at d, adapting it to be 35 secured over the outlet-pipe by a bayonet-joint, and provided at its lower end with short pins d' similar to those on pipe C.

E represents a cap to fit over and close the lower end of the conduit-pipe, it being also 40 slotted, as at e, for attachment by bayonet-joint.

Inside of head B, a short distance above the top of stack A, is a series of lugs, b, for supporting the spark-arrester, which arrester will 45 now be described.

F represents an inverted cone made of wire-cloth. The base of this cone is secured between two annular plates, G G', (the latter, G', having a downwardly-extending flange, g',) 50 and its apex is covered by a metallic cap, H. Metallic braces I, secured to the cap and to

the under side of plate G', serve to support the cone and keep it in shape, and the meeting edges of the wire-cloth forming the cone are secured by means of a metallic strip, 55 J, the sides of which are folded over the edges of the cloth, as clearly shown in Fig. 1.

K represents a downwardly-extending and outwardly-flaring wire-cloth apron of a size at its bottom to fit the interior of head B. The 60 upper end of this apron, also, is secured between plates G G', which are clamped together by screws. The apron is held in shape by the rim on plate G', and by a metallic hoop, L, at its bottom, to both of which it is secured, and 65 also by metallic braces M, secured to the hoop and to plate G'.

N represents springs, made of any suitable metal, secured at their upper ends to the plate G, while their lower ends are hooked under 70 hoop L, which allows them to yield when putting the arrester in place in the head.

When the spark-arrester is in place in head B, the hoop of the apron rests on lugs b, the apex of the cone extends down into the top of 75 stack A, and springs N impinge against the inner side of the head with sufficient force to hold the arrester in place. Thus it will be seen that while the arrester is amply secured when in use, it may be readily and easily removed when desired. While the engine is in 80 operation, the sparks and cinders are thrown up against the cone and by it deflected against the apron, which in turn directs them down into the annular space between the stack and 85 the bottom portion of the head, whence they pass out at the outlet and are conveyed away by the conduit. When the engine is not in use, the conduit may be detached and its cap 90 used to cover the outlet-pipe.

Having thus described my invention, what I claim as new, and desire to secure by Letters Patent, is—

1. The combination, with the smoke-stack and the head, the former extending up into 95 the latter, which is provided with lugs on its inner side, of a removable spark-arrester consisting of an inverted wire-cloth cone secured at its base between annular plates, a downwardly-extending and outwardly-flaring wire-cloth apron secured at its top between said 100 plates, the bottom of the apron fitting the in-

terior of the head and resting on the lugs, and laterally-acting springs for securing the arrester in place, substantially as described.

2. The combination, with the smoke-stack 5 and the head, the former extending up into the latter, which is provided with lugs on its inner side above the top of the stack, and an outlet at the junction of the stack and head, a conduit removably attached to the outlet, and 10 a removable cap for the conduit, of an inverted wire-cloth cone whose apex extends into the stack and whose base is secured between annular plates, a downwardly-extending and outwardly-flaring wire-cloth apron

secured at its top between said plates, the bottom of the apron fitting the interior of the head and resting on the lugs, and laterally-acting springs secured to one of the annular plates and hooked under the lower edge of the apron, substantially as described, and for the 15 purposes set forth.

In testimony whereof I hereunto affix my signature in presence of two witnesses.

JAMES M. C. TYNER.
